UNITED STATES PATENT OFFICE.

ROBERT L. KEITH, OF BRAZIL, INDIANA.

WAGON-BODY LIFTER.

SPECIFICATION forming part of Letters Patent No. 406,352, dated July 2, 1889.

Application filed February 20, 1889. Serial No. 300,563. (No model.)

To all whom it may concern:

Be it known that I, ROBERT L. KEITH, a citizen of the United States, residing at Brazil, in the county of Clay and State of Indiana, have 5 invented certain new and useful Improvements in Wagon-Body Lifters; and I do hereby declare the following to be a full, clear, and exact description of the invention, such as will enable others skilled in the art to 10 to which it appertains to make and use the same.

My invention relates to wagon-body lifters; and it consists of such means and their arrangement, as hereinafter described and claimed, as will simplify and render more efficient this class of inventions.

My invention is illustrated in the accompanying drawings, in which—

Figures 1 and 2 are side and end views, respectively, in elevation, and Fig. 3 a plan.

Referring to the drawings, the frame for supporting the lifting device is composed of 20 four vertical posts A, each pair of which are united by a top cross-piece B.

C CD D represent, respectively, the side and 25 end pieces of a frame, to which the lower ends of the vertical posts are secured, which frame may be set in or on the floor or ground, or the vertical posts may be tenoned into the floor-timbers of a barn or shed.

F is a windlass journaled in brackets G, 30 that are secured to the top cross-pieces B, with one end of the windlass extending beyond the frame and provided with handles h.

I is a ratchet secured to the windlass between the handles h and the frame, and controlled by a pawl K, pivoted to a cross-piece B.

M is a brake pivoted to a bracket l on cross-piece B.

The brake M is provided with a grooved or 40 cut-out portion m', adapted to close upon the windlass at the point m², and is also provided with a cord m³ and handle m⁴, with which to operate it.

P P are hanging frames, each composed of 45 two upright and two cross pieces, and each suspended directly from the windlass by a cord s. When not in use the frames P are drawn up to the windlass and there held.

When it is desired to raise a wagon-body, the wagon is driven between the posts A, the 50 frames P lowered and placed under the ends of the body, and the windlass turned until the body is raised to the desired height, where it is held by the pawl engaging with the ratchet. When it is desired to lower the body, the pawl 55 is raised; but to prevent the sudden fall the brake M is applied, by which not only the force of the fall is controlled, but the body can be held at any point.

The form of the lifting-frames P is advan- 60 tageous, as they serve as cages, extending under the body its entire width and supporting the sides, thus providing for a uniform strain and support and being superior to hooks, or to lifts having but a bed-frame with chain or 65 cords attached thereto, which are apt to scratch or otherwise injure the body and to yield to strain and slipping at different points.

It will be seen that my apparatus can be readily used to hoist other objects than wagon- 70 bodies.

What I claim is—

A wagon-body lifter consisting of the frame composed of the uprights and cross-piece A B, side and end pieces C D, in combination 75 with a single windlass F on the top of the frame, the handles, brackets G, secured to the cross-piece B, and in which the said windlass is journaled, the ratchet I, secured to the said windlass F, and pawl K, pivoted to the top 80 cross-piece B, the hanging frames P P, composed of upright and cross pieces and adapted to extend under the wagon-body and up its sides, cords supporting said frames from the windlass, and the brake M, pivoted to a bracket 85 on cross-piece B and provided with a groove m', to close upon the said windlass F, and with a cord and handle with which to operate it, substantially as described.

In testimony whereof I affix my signature in 90 presence of two witnesses.

ROBERT L. KEITH.
